UNITED STATES PATENT OFFICE.

REGINA MANN, OF NEW LONDON, CONNECTICUT.

DESIGN FOR A CITRUS-FRUIT SERVING DISH.

Application filed October 19, 1927. Serial No. 23,798. Term of patent 3½ years.

To all whom it may concern:

Be it known that I, REGINA MANN, a citizen of the United States, residing in New London, in the county of New London, in the State of Connecticut, have invented a new, original, and ornamental Design for a Citrus-Fruit Serving Dish, of which the following is a specification, reference being had to the accompanying drawing, forming a part thereof.

I claim:

The ornamental design for a citrus fruit serving dish as shown.

REGINA MANN.
